FIGURE 1 is an elevational view of a container for oil products or the like showing my new design;

The essential features of my design are indicated by solid lines and reside in a columnar-type container for oil products or the like having a pair of spaced ribbed band areas extending about its columnar periphery, the band areas being sufficiently spaced from one another to permit an identifying mark to be located therebetween. The non-illustrated tops and bottoms of the containers of FIGURES 4 to 6 are like those shown in FIGURES 2 and 3.

I claim:

The ornamental design for a container for oil products or the like, as shown and described.
